UNITED STATES PATENT OFFICE.

CLARENCE E. STEERE, OF CHICAGO, ILLINOIS, ASSIGNOR TO COX MULTI-MAILER CO., OF CHICAGO, ILLINOIS, A CORPORATION OF MAINE.

EMBOSSING-MACHINE.

1,178,963.

Specification of Letters Patent. Patented Apr. 11, 1916.

Application filed June 10, 1914. Serial No. 844,110.

To all whom it may concern:

Be it known that I, CLARENCE E. STEERE, a citizen of the United States, residing at Chicago, in the county of Cook and State of Illinois, have invented certain new and useful Improvements in Embossing-Machines, of which the following is a specification.

My invention relates to improvements in stamping or embossing machines and has 10 more particular reference to improvements in machines of this character for stamping or striking up letters or other printing characters on such material as sheet metal to be used as so-called printing plates for addressing machines and the like.

One of the objects of my invention is to provide a machine of this character which will be simple, durable and reliable in construction and effective and efficient in operation.

Other objects of my invention will appear hereinafter.

Referring to the accompanying drawings: Figure 1 is a view in side elevation of a 25 machine embodying my invention; Fig. 2 is a plan view of said machine; Fig. 3 is a vertical longitudinal section of the machine taken substantially on the line 3—3 of Fig. 2; Fig. 4 is a transverse vertical section taken 30 substantially on the line 4—4 of Figs. 2 and 3; Fig. 5 is a staggered detail section substantially on the line 5—5 of Fig. 4; Fig. 5^a is a detail section on the line 5^a—5^a of Fig. 5; Fig. 6 is a transverse vertical section 35 substantially on the line 6—6 of Fig. 3; Fig. 7 is an enlarged detail section substantially on the line 7—7 of Fig. 3; Fig. 8 is a detail view in elevation of the die-carrying or embossing wheels and the mechanism for 40 actuating them; Fig. 9 is an enlarged detail view, partly in section, of the escapement mechanism and associated parts shown in the upper part of Fig. 5; Fig. 10 is a detail view of the mechanism shown in Fig. 9, this 45 view being taken substantially on the line 10—10 looking in the direction of the arrows; Fig. 11 is a detail view, partly in section, taken substantially on the line 11—11 of Fig. 4; Fig. 12 is a detail section on the 50 line 12—12 of Fig. 10; Fig. 13 is a detail perspective of the escapement dog; Fig. 14 is a detail fragmentary view of a portion of one of the die-carrying wheels; Fig. 15 is a detail section on line 15—15 of Fig. 3, and

Fig. 16 is an enlarged perspective of the 55 cams for operating the die-carrying wheels.

The machine shown in the drawings and which illustrates one embodiment of my invention, has been designed more particularly for the purpose of embossing or raising 60 letters or other printing characters from small plates or strips of sheet metal such as are used as printing plates in connection with addressing machines and the like. It will be obvious, however, to one skilled in the 65 art, after having obtained an understanding of my invention from the disclosures herein made, that the machine may be modified or used for operating upon other materials without departing from the scope and spirit 70 of the invention, and I wish it to be so understood.

My invention will be described in connection with the particular machine shown in the drawings. A description of the printing 75 plates is unnecessary except to say that in this particular instance they are made of flat sheet metal rectangular in shape and the letters or printing characters are struck up integrally from the body of the plate. One of 80 these plates is shown in section at A in Figs. 3, 4 and 8. By reference to the drawings it will be observed that the various operating parts and mechanisms are mounted in compact operative relation in a substantial 85 supporting frame B so as to form a complete operating unit which may, if desired, be readily carried about. The printing plates upon which the letters or other printing characters are to be embossed are adapted to 90 be positioned between two rotary die-carrying or embossing wheels C. These die-carrying wheels are located preferably in the front portion of the frame adjacent the keyboard so that the operator may at all times 95 observe the work of the machine, thus giving the advantage of making this machine a so-called "visible" machine. Each embossing wheel or member C has an outstanding annular flange or rim 1, so to speak, in which a 100 plurality of radial slots are cut, the number of these radial slots corresponding preferably to the range of letters or printing characters which the machine is designed to emboss upon the printing plates A. These 105 radial slots open through the periphery of the flange 1 and are preferably equally spaced circumferentially as shown more

clearly in Figs. 3, 4 and 8. Each radial slot carries a stamp or embossing die 2 the outer end of which projects beyond the periphery of the flange 1 and is formed to stamp the particular characters desired. In the machine shown the dies are complementary and the lower embossing wheel carries the female dies and the upper embossing wheel C carries the male dies so that the letters or printing characters will be raised up from the lower or underface of the printing plate A. The purpose of this is to permit the operator to readily read the letters on the upper face of the printing plate A while said printing plate is in position. In this manner the stamped or embossed words on the printing plate will read in regular order instead of backward and the operator can thereby observe at all times just what letters are being stamped upon the plate. The stamping dies 2 are comparatively short and their inner ends rest upon the edge or outer periphery 3 of a thrust ring or plate which is set into the front face of each of the die-carrying wheels. A clamping ring 4 is then fastened or bolted to the front face of the flange 1 to hold the dies in place. This construction serves to rigidly hold the dies in their proper position and at the same time permit any one or more of the dies to be readily removed or replaced in case they become damaged. The two die-carrying wheels C are preferably identical in construction and are peripherally opposed one above the other or 35 in edgewise relation, preferably so that they lie in practically the same vertical plane when they are in embossing position. They are mounted upon and driven by the shafts 6 and these shafts are journaled in comparatively long bearings or mountings 7. These bearings each have at their inner ends trunnions 8 which are mounted upon pivot studs 9. These studs are supported on the side members of the frame. They terminate 40 short of each other to provide a space therebetween and are axially alined. They form a common pivotal axis about which the die-carrying wheels C and bearings 7 can be bodily swung or rocked. The pivot studs 9 and the die-carrying wheels C are arranged in such position that the axes of rotation of the wheels C lie in a plane which passes through or includes the point in which the complementary dies on the die wheels meet, 45 hence said plane is perpendicular to the vertical plane in which the die-carrying wheels lie when said die-carrying wheels are closed together and in their embossing or stamping position. The printing plate A is adapted to be positioned by means of the carriage, later to be described, in this plane which includes the axis of the pivot studs 9, as shown clearly in Fig. 8. By this construction and arrangement of the parts, of course the die-carrying wheels necessarily

move bodily on arcs the center of which is the axis of the pivot shaft 9. But although these die-carrying wheels do move in arcs it will be particularly noted that the dies in both wheels will approach and recede or 50 move away from the printing plate A in a line which is so close to a vertical line at right angles to the plane of the printing plate that practically no lateral movement will be imparted to the plate or the metal 55 thereof during the actual compression of the plate between the two dies. To make this clearer it will be observed that for a short distance above and below the printing plate A the curvature of the arc in which the opposed 60 or complementary dies on the die-carrying wheels move is so negligible as to practically amount to a straight vertical line, hence the dies will approach and recede from the printing plate on a vertical line which is practically exactly at right angles to the plane of the plate, thereby eliminating any errors or inaccuracies which would occur if the dies were not arranged so that they would move in a vertical line. The distance to which the 65 die-carrying wheels are separated need in practice be just sufficient to permit the convenient insertion or removal of the printing plate A. The bodily movement of both of the die wheels also has the advantage of 70 readily stripping with respect to the plate A; that is to say, the dies of both wheels positively move entirely clear of the plate A after each embossing operation and hence cannot "stick" to the plate. 75

The inner or rear ends of the die wheel shafts 6 carry gear wheels 10 (Figs. 1, 2, 3 and 8) which are identically alike and of the same size and which mesh with and are driven by an intermediate or common gear 11 positioned therebetween. Referring more particularly to Figs. 1 and 3, it will be seen that the intermediate gear 11 is rotatably mounted upon a long main shaft 12 of the machine. The forward end of this shaft is 80 journaled in a bearing 13 which is positioned, as will be seen, just in the rear of the die-carrying wheels C, and the rear end of the shaft is journaled in a similar bearing 14. The forward bearing 13 is formed on a bridge member 15 of necessary strength which, as shown in Fig. 2, spans the two side members of the frame B. The longitudinal axis of the main shaft also lies in the plane which passes through the axis of pivots 9 85 and the printing plate A. This shaft is preferably driven constantly in any suitable manner. In the construction shown the rear end of the shaft carries a large fly-wheel 16 which can be driven by a belt from an electric motor or other source of power (not shown). The gear 11 drives the gears 10, and through the medium of the shafts 6, the die-carrying wheels are given their rotary motion. It will be noted that the die- 90

carrying wheels are thus rotated in the same direction; that is to say, the portions of their peripheries which are adjacent each other at any instant during their rotation move in opposite directions. Among other advantages this prevents the operator from entangling the fingers between the die-carrying wheels and crushing them. This is obvious, because while one die-carrying wheel may have the tendency to carry the operator's fingers in between the wheels the other die-carrying wheel has an equal tendency of throwing out the finger so that in practice I find it almost impossible for the operator to become injured. The train of gears for driving these parts, comprising the individual gears 10 and the common intermediate gear 11 are all arranged in a substantially vertical plane which passes through the axis of the pivots 9. As before mentioned, and as shown in Fig. 8, the die-carrying wheels need only be separated just a sufficient amount to allow the convenient insertion or removal of the printing plate A. While the opening and closing of the die-carrying wheels about the pivots 9 as a common axis shifts the gears 10 slightly laterally with respect to the intermediate gear 11 this movement is so negligible that no special provisions need be made. Just in the rear of the forward bearing of the main shaft, this shaft has a squared portion 17 on which a thimble 18 is mounted so as to be rotated by the shaft but slide longitudinally of said shaft. A sleeve 19 surrounds the thimble 18 and moves longitudinally with said thimble 18. The sleeve, however, is fixed against rotation as will later appear. There is considerable longitudinal thrust between the sleeve and the thimble and in order to take up this thrust each is provided with a flange at their rear ends between which flanges is interposed a ball thrust bearing 20. This construction permits the thimble to rotate relatively and perfectly free with respect to the sleeve 19 and at the same time reduces the friction therebetween to a minimum. On each side of the sleeve 19 is a toggle, each toggle comprising two links 21 (see Fig. 8). The two links of each toggle are pivoted together and pivoted to the sleeve 19 at 22 to form the knuckles of the toggles, and as above intimated, the toggles thus hold the sleeve 19 against rotation. The other ends of the respective toggle links are pivotally connected at 23 to the rear ends of the levers 25. These operating levers 25 (see Figs. 2, 3 and 8) are pivoted at 26 to the frame of the machine and their forward ends are pivotally connected at 27 to the bearings 7 which carry the die-carrying wheels. Thus when the thimble 18 and sleeve 19 are moved forward longitudinally along the main shaft 12 the toggles will tend to straighten out and will rotate the operat-

ing levers 25 about their pivots, and these levers in turn will actuate the bearings 7 and the die-carrying wheels to close them together and make the impression upon the printing plate A positioned therebetween. 70

It will be noted that there is a set of operating levers and toggles on each side of a vertical plane passing through the longitudinal axis of the die-carrying wheel shafts 6 so that the power for actuating each die-carrying wheel is applied at two points (the pivots 27 of the operating levers 25) which are spaced apart a considerable distance laterally, and in consequence the power will be applied in a balanced condition and all tendency of the shafts 6 and bearings 7 to spring laterally is practically eliminated. The operating levers 25 are connected to the bearings 7, through the medium of the pivots 27, as close to the die-carrying wheels 80 as possible so that the power is applied to the die-carrying wheels in practically a vertical plane which is almost coincident with the vertical plane in which the die-carrying wheels lie. In other words, by means of this construction the power is applied to the die-carrying wheels almost directly at the points where they meet and make the impression upon the printing plate. This insures a powerful direct actuation of the die-carrying wheels by means of the toggle system of levers. The power applied to move the sleeve 19 and thimble 18 is greatly multiplied through this system of levers and the die-carrying wheels will be powerfully actuated. 90

The inner or rear end of the thimble 18 (see Figs. 2, 6, 7, 8 and 16) carries an annular cam E which is the exact counterpart of a similar cam F secured to the end of the gear 11. Both of these cams have corresponding high parts E¹ and F¹ and low parts E² and F², respectively, these high and low parts being preferably arranged so that they occupy equal portions of the circle 105 in which the cam is disposed. In other words, they are constructed so that the high part of one cam fits the low part of the opposed cam. Hence, when the cams are rotated relatively the high parts of one cam ride up on the high parts of the other cam and a relative longitudinal movement of the cams will take place. This is the manner in which longitudinal movement is imparted to the thimble and sleeve 19 for actuating 110 the toggles to close the die-carrying wheels, as previously described. 115

As before mentioned the cam F is fastened to the gear 11 for rotation therewith and the power for driving the gear 11 is 125 derived from the main shaft 12 through the medium of the thimble 18 and the two cams E and F. That is to say, when the cams are in such position that the high parts of each cam occupy a position within the low parts 130

of the other cam, which condition is illustrated in Fig. 8 and corresponds to the open position of the die wheels, the thimble 18 being squared on to the shaft will drive 5 the gear 11 through the two cams. It will be remembered that the die wheels and their operating parts are driven from the central or intermediate gear 11 and since there is no load to speak of on these parts very little 10 power is required to rotate them. In consequence, therefore, the friction between the two cams, when their high and low parts are interfitted, is sufficient to drive the dis- 15 carrying wheels but as a further precaution I provide means for locking the two cams together. In the structure shown this lock consists of a dog 30 (see Figs. 6, 7 and 16) one end of which is fastened in the end of a shaft 31 which passes through the cam F 20 and gear 11, and the other end of which is adapted to engage one of the notches or teeth 32 in the cam E. The teeth 32 are formed on the inner periphery of the cam E at points corresponding to the centers of 25 the high parts E¹ of said cam. The end of the dog 30 occupies a position corresponding to the center of one of the low parts F² of the cam F. Thus when the high and low parts of the cams register with each other, 30 such as shown in Fig. 8, the dog 30 will be in position to engage one of the teeth 32 of the cam E and thus lock the cams together. The main shaft 12 is preferably constantly 35 rotated, hence when the two cams are in register the die-carrying wheels will likewise be rotated. The two die wheels will continue to rotate until one of the cams is stopped so that a relative rotation of the two cams will take place. In the machine 40 shown this control of the die-carrying wheels and the selection of the proper complementary dies on said wheels is accomplished through the medium of a series of stop devices corresponding to the letters or 45 other printing characters on the die-carrying wheels.

The gear 11 carries a comparatively long outstanding substantially radially disposed arm 35 which rotates with the gear 11 and 50 which sweeps around in a vertical plane just in front of a large fixed disk or member G. The shaft 31 on which the dog 30 is mounted also has a substantially radially disposed arm 36. This arm is positioned adjacent 55 the arm 35 but it is normally held at an angle to the face 37 of the arm 35 by means of a light curved spring 38. This spring thus yieldingly holds the dog in engagement with one of the teeth 32 on the 60 cam E.

The supporting or mounting member G is comparatively thick and solid and is removably mounted midway of the two side members of the frame in a vertical plane. 65 It has a large central opening 39 to allow

room for the main shaft. This member G carries a plurality of stop pins 40 which are adapted to be projected into the path of the revolving arms 35 and 36. Referring to Fig. 6 it will be noted that these stop pins are 70 preferably arranged in two annular concentric series of rows. The pins in each row are equally spaced apart and the pins of the inner row are staggered with respect to those of the outer row or series so that radial lines drawn from the axis of the shaft 12 and through the axis of the pins on the inner rows will pass midway between the pins of the outer row. The number of pins in these series correspond to the number of 75 printing characters on the die-carrying wheels so that each pin represents a corresponding letter or printing character on the die-carrying wheel. They are so positioned with respect to the dies in the die-carrying 80 wheels that each pin will operate to stop the die-carrying wheels in position to stamp or emboss the printing character which it represents on the plate A. Each one of these pins are operated by a key H positioned 85 preferably in the lower forward end of the frame, all of the keys being arranged in suitable keyboard form similar to a linotype machine or a typewriter or any standard 90 keyboard arrangement. Each of the stop pins 40 is carried in small bushings 41 which are set in corresponding holes in the mounting plate G so that the pins may be readily removed or replaced individually. Each 95 pin is surrounded by a coil spring 42 which yieldingly holds the pin with its forward end flush with the front faces 43 of the plate G and hence out of the path of the arms 35 and 36. The rear end of each stop pin is 100 engaged by one arm of a small bell crank 105 lever 44 which is pivoted at 45 on the end of a small pin driven into the mounting plate G. The other arm of the bell crank lever is pivotally connected to one end of a link 46, 110 the other end of which is connected at 47 115 to the rear end of a key-lever 48.

The key-levers 48 are preferably all positioned in substantially the same horizontal plane in the lower part of the frame of the machine and they are all pivoted upon a 115 transverse shaft or pivot member 49. The forward ends 50 of the key-levers are all upturned and positioned in the proper keyboard arrangement. They carry the key buttons H for convenient operation. Thus 120 it will be seen that when the operator presses the key H, the corresponding stop pin will be projected forward into the path of the rotating arms 35 and 36 and will stop the rotation of said arms, thus holding the gear 125 11 and the cam F against rotation. This, of course, stops the gear wheel 10 and consequently the die-carrying wheels G, in position so that when said die-carrying wheels 130 are brought together they will stamp or em- 135

boss the corresponding printing character upon the plate A. The rotating arm 36, of course strikes the projected pin 41 first and the momentum of the parts will cause 5 this arm to be rotated until it abuts the face 37 of the arm 35, as shown in dotted lines in Fig. 7. The slight relative rotation of the arm 36 throws the dog 30 clear of the tooth 32 and unlocks the cams and the cam 10 F is thus held against rotation but the cam E, being driven by the main shaft, continues to rotate and its high parts E¹ ride on the high parts F¹ of the cam F. This operation of course moves the thimble 18 and sleeve 15 19 longitudinally forward, and through the medium of the toggles and levers previously described, brings the two die-carrying wheels together with a powerful pressure against the printing plate A. This position 20 of the parts is shown in the sectional view of Fig. 3.

In practice I preferably allow slight play between the gears 10 and the intermediate gear 11 for various obvious reasons, such 25 as the reduction of friction and the free running of the die-carrying wheels and the parts which carry said wheels. In the actual formation of printing characters upon the printing plate A, however, it is 30 decidedly advisable that the complementary dies on the two wheels be brought together in exact alinement so that they will register perfectly and emboss a clean perfect letter 35 on the plate A. No lost motion or play must be allowed between the die-carrying wheels during this actual stamping operation, and in consequence I provide an alining mechanism which exactly positions the die-carrying wheels with respect to each 40 other as they come together.

Referring more particularly to Figs. 3 and 14, it will be observed that the rear faces of the die-carrying wheels are provided with a series of radial slots 60, each 45 slot of which corresponds exactly in relative position to an embossing die 2 on the wheel. Just above and below the stamping position, that is the plane in which the plate A lies, is a pair of alining pins 61 (see Fig. 3). In the forward end portions of these pins 50 are journaled bushings 62 which are eccentrically mounted in the ends of suitable sockets or bores 63 in the frame. These pins have enlarged heads 64 at their rear ends 55 which are slidable in the bores 63 and between these heads 64 and the bushings 62 are coil springs 65 acting to yieldingly hold the forward ends of the pins substantially flush with the ends of the bushings, that is 60 to say, the springs tend to hold the alining pins 61 out of the path of the die-carrying wheels C. The rear ends of the pin 64 abut against the end of the sleeve 19, and when the sleeve 19 is moved longitudinally 65 forward the pins are likewise moved and

their forward ends projected into the slots 60 in the rear faces of the die-carrying wheels. The alining pins 61 are slightly tapered at their ends and the edge portions of the walls of the slot 60 are beveled as at 70 66 so that the pins will properly enter the alining slots 60 and slightly move the die-carrying wheels into exactly alined position in the event that they should be slightly out of position. It will be noted that these 75 alining pins are positioned very close to the point where the impression is made upon the plate and in consequence eliminates all chance of errors or inaccuracies. The alining pins are so timed with respect to the 80 other parts that they begin to move toward the alining slots 60 just after the dog 30 has been released from engagement with the tooth 32 of the cam E so that the die-carrying wheels have actually come to a dead 85 stop before the alining pins enter said alining slots. In a machine of this character it is desirable to remove the stopping pin 40 from the path of the rotating arms after the arms have been stopped and while the 90 operation of making an impression upon the plate A is being performed. In the structure shown in the drawings I withdraw the stop pins 41 by actuating the particular key-lever which is depressed. In the forward 95 part of the frame B beneath the key-levers is a transverse shaft 67 and this shaft carries a common or universal bar 68 which is adapted to be rotated in and out of engagement with the key-levers when the shaft is 100 rotated. This bar normally occupies a position below the key-levers, that is out of the path thereof, so as to permit their depression. It is yieldingly held in this position by a suitable spring 69, one end of which is 105 anchored to the frame of the machine and the other end to a small arm 70 on the shaft 67 (see Figs. 3, 4 and 5). Substantially beneath the operating toggles is a long 110 transverse shaft 71 journaled in the frame of the machine and this shaft carries two arms 71 and 74 rigidly connected therewith. The arm 72 is pivotally connected at its upper end to a lug 73 on the longitudinally movable sleeve 19 (see Figs. 3 and 15). 115

The arm 74 extends downwardly to the lower part of the frame and is given a horizontal turn at its lower end 75 and this end is connected by a link 76 to the short arm 70 on the transverse shaft 67, thus when the 120 thimble 18 and sleeve 19 are moved forwardly the arms 71 and 74 and shaft 71 are rotated, thus rotating the universal bar 68. This bar acts upon the under side of the particular key-lever which has been depressed 125 and restores the lever to its original position. The movement of the key-lever of course withdraws the stop pin 41 from the path of the rotating arms 35 and 36. These parts are so timed that the end of the stop 130

pin 41 is not completely withdrawn from engagement with the arm 36 until the die-carrying wheels have just made their impression upon the plate A. The arm 74 is connected with the link 76 by means of a lost motion connection so that when the arm 74 moves rearwardly it will pull on the link 76 and rotate the universal bar, but when the arm 74 moves in the opposite direction during the restoration of the parts it will move relatively to the link and will not thereby actuate said link and universal bar. Any suitable connection may be provided at this point. In the construction shown, the end 75 of the arm 74 has an opening or hole through which the link 76 extends. The end of the link 76 carries a nut 77 which is engaged by the end 75 of the arm during its rearward movement. This arrangement also provides an adjustment whereby the proper position of universal bar may be properly determined.

Fig. 3 shows the die-carrying wheels on the point of being restored. In this condition of the parts the pin 41 has just been completely withdrawn and the key-lever restored. Since the pin 41 is now out of the path of the rotating arms 35 and 36 the arm 36 is relatively rotated slightly by its spring 38 which restores the dog 30 to a position where it will engage the teeth on the cam E when said cams again register. The withdrawal of the stop pin releases the arms 35 and 36, the gear 11 and cam F from said stop pin 41 but the cam F and gear 11 cannot as yet rotate for the reason that the alinement pins 60 hold the die-carrying wheels against rotation, thus holding the gears 10 and intermediate gear 11. Since the main shaft 12, however, is constantly rotating, the cam E will continue its rotation and its high parts will ride down, so to speak, into the low parts of the cam F and at the same time the thimble 18 will move longitudinally rearward under the action of the springs 65 which surround the alinement pins 61. At the same time the toggles are gradually collapsed and the levers which they operate will swing or rock the die-carrying wheels apart. These parts all operate in proper timed relation and by the time the two cams E and F again register the alinement pins will be withdrawn and the die-carrying wheels swung completely open.

The timing of these parts is such that the alinement pins will be withdrawn from the alinement slot 60 slightly before the cams reach a complete registering position. This unlocks the die-carrying wheels and the parts connected therewith and leaves them free to be rotated slightly before the cams actually reach their complete registering position. The friction incident to the pressure (caused by the springs 65) of the cam E upon the cam F will then come into play to

start the die-carrying wheel rotating. There is a slight inertia to overcome in starting the rotation of the die-carrying wheels and the other rotating parts and in consequence the friction between the two cams will gradually start the die-carrying wheels and rotating parts. That is to say, after the alinement pins have been withdrawn there will still be a relative "slip" between the two cams before the cam E completely registers with the cam F, and during this slight relative "slip" the friction between the two cams starts the rotation of the die-carrying wheels and gradually brings them up to speed, thus avoiding sudden strains or blows on the parts. By the time the two cams completely register the die-carrying wheels will be fully up to speed, and the dog 30 being positioned by the spring 38, will engage one of the teeth 32 of the cam E and lock the cams together again. It will be noted also that in stopping the rotation of the die-carrying wheel a cushion effect occurs when the arm 36 strikes the projected pin. This is obvious for the reason that the blow which the arm strikes the pin is counteracted by the spring 38 during time the dog 30 is being disengaged from the cam E and also while the cam E rides up on the high parts of the cam F.

Since the arms 35 and 36 are normally at an angle with respect to each other and hence spaced apart during their rotation there is a possibility that the operator might depress a key and project one of the stop pins forward into the space between the two arms 35 and 36 (see Fig. 6). Should this happen it would readily be seen that the arm 36 and hence the dog 30 would not be operated to release the cams and the parts likely would become damaged. To avoid this condition, however, I provide the rear face of the arm 35 with two slots 35^a. These slots are deep enough so as to permit the arm 35 to pass over the stop pin in the event that said stop pin should be projected into the space between the two arms 35 and 36. The rotating arms will thus pass said pins without being stopped thereby until they have made one complete rotation and again arrive in proper position with respect to the projected stop pin.

The plate A is removably mounted in a suitable carriage K so that it may be moved in both directions for line spacing and letter spacing of the printing characters. This carriage in the structure shown comprises a long narrow rectangular open frame which is adapted to slide or shift longitudinally of itself in a pair of guideways 80. These guideways are connected at their ends by the bars 81 and form therewith a sub-carriage which can be shifted in a direction transverse to the longitudinal direction of movement of the carriage K for spacing the

lines of printed characters on the plate. The connecting bars 81 of the sub-carriage are mounted to slide in this direction in suitable guideways or members 82 fastened to the side members of the frame B, as clearly shown in Figs. 2, 3 and 4. The shifting of the sub-carriage for spacing the lines of printed characters on the plate may be accomplished in any suitable manner, such for instance, as shown more particularly in connection with Fig. 11. The sub-carriage which comprises the guideways 80 and end connecting bars 81 has a small toothed rack 83 on its under side at each end, and these racks mesh with and are driven by a pinion 84 mounted on the side members B of the frame. A shaft 85 extends transversely of the frame and carries two segmental gears 86 which mesh with and drive the pins 84, and this shaft extends through the frame at one side and carries at its outer end a suitable hand wheel 87 or other device for conveniently rotating the segments 86. A segment 88 is also attached to the shaft 85 and has a series of notches 89 in its end. These notches coöperate with a roller 90 on a pivot arm 91, the roller 90 being yieldingly held in engagement with the segment by means of the spring 92. These notches correspond to the proper line spacing for the plate A and coöperate with the roller 91 to yieldingly hold the carriage in any position to which it is shifted for line spacing. The shifting of the carriage K longitudinally, that is transversely of the frame, for spacing of the letters or printing characters in the line thereof is accomplished by an escapement mechanism which is controlled by the mechanism which operated the die-carrying wheels and not directly by the keys. On the under side of the carriage is a long toothed rack 93 (see Figs. 5, 5^a, 9, 10, 12 and 13), which rack meshes with and drives a pinion 94. This pinion 94 is mounted upon a shaft 95 which is journaled in a bearing 96 in the frame. Positioned in the front of the frame at one side and just below the carriage is a drum 97 containing a spiral spring 98. This spring tends to rotate the drum in one direction. A long band or tape 99 (see Figs. 2, 5 and 5^a) is attached to the opposite end of the carriage and is adapted to be wound around the drum 97. Thus the carriage is constantly under tension of the spring drum 98 which tends to move it in the direction of the arrow (Fig. 10). The shaft 95 which carries the pinion 94 also has a toothed escapement wheel 100. The tension which the spring drum 97 exerts upon the carriage constantly tends to shift it in the direction of the arrow (Fig. 10) and thereby to rotate the pinion 94 and the escapement wheel 100. The escapement wheel, however, is normally held against rotation by a rocking lever M which is pivoted to the frame at 101. This lever rocks in a plane transverse to the plane in which the escapement wheel lies, and it has a fixed dog or tooth 102 at its upper end which engages one of the teeth of the escapement wheel and prevents said wheel from rotation. This fixed tooth 102 is preferably substantially as thick as the escapement wheel and when the rocking lever M is rotated upon its pivot this tooth will be moved laterally out of engagement with the teeth of the escapement wheel, as shown in dotted lines in Fig. 9. The rocking lever M also carries a dog 104 which is pivoted at 105 upon said lever. A spring 106 is also carried by the lever M and constantly presses upon the lower arm of the pivot dog 104 to yieldingly hold the upper end of said dog some distance in advance of the tooth 102; this distance being substantially the equivalent of one tooth on the escapement wheel 100. Thus when the lever M is rocked about its pivot and the tooth 102 moved laterally out of engagement with the tooth of the escapement wheel the yielding dog 104 will enter into engagement with the escapement wheel, one tooth in advance of the escapement wheel tooth which is engaged by the tooth 102, and as soon as the tooth 102 leaves the tooth of the escapement wheel the escapement wheel, being under tension by the spring drum 97, will rotate and carry with it the yielding dog 104. The lever M also has a shoulder 107 (see Fig. 10) which acts as a stop for the dog 104 to limit the movement thereof so that its forward face 108 will be flush with the forward face 109 of the dog 102 (see Figs. 10 and 13). When the escapement lever M is rotated in the other direction, that is, to the position shown in full lines in Fig. 9, the yielding dog 104 will be moved laterally out of engagement with the tooth of the escapement wheel, and this same tooth of the escapement wheel will be engaged by the tooth 102 of the escapement lever. In other words, in this latter direction of rotation of the escapement lever M the escapement wheel will not be permitted to rotate. By this construction the carriage will shift a distance equal to one tooth on the escapement wheel and this distance governs the spacing of the letters or printing characters which are stamped upon the printing plate A. In the structure shown, this escapement, as before intimated, is actuated by the mechanism which actuates the die-carrying wheel so as to be independent of the keys. By reference to Figs. 3, 5, 9 and 10 it will be seen that the rocking escapement lever M has a link 110 which is pivotally connected to its lower arm. The end of this link passes through an opening 111 in a rib 112 on the upper arm 72. A couple of nuts 113 are threaded on to this link 110 and abut against the rib 112 of said arm 72, 130

thus when the arm 72 is rotated by the movement of the thimble 18 and sleeve 19 in the direction to close the die-carrying wheels said lever will also rock the escapement lever M through the medium of the link 110 so as to throw the escapement lever M in the position shown in full lines in Fig. 9. The rotation of said lever M in this direction, however, does not, as above explained, permit the operation of the escapement wheel. When said escapement lever, however, is rotated in the reverse direction, that is to the position shown in dotted lines in Fig. 9, the escapement wheel will, as above explained, rotate one step. This direction of rotation of the lever M corresponds to the opening movement of the die-carrying wheels. In other words, the carriage is not operated to shift the space of one letter until the die-carrying wheels have made their impression and commenced to open. The connection between the link 110 and the arm 72 permits the arm 72 to return independently of the link 110, and in order that the escapement lever will be operated or thrown to the position shown in dotted lines in Fig. 9, I provide a spring 114 which presses upon said lever M and throws it to said position when the arm 72 returns to its normal position. This the initial movement of the arm 72 during the closing of the die-carrying wheels does not operate the escapement but merely places the escapement lever in condition so that when the die-carrying wheels upon and the arm 72 returns to its original position, the spring 114 will throw the escapement lever and cause the escapement wheel to rotate one step. This arrangement which I have just described is thus accomplished automatically during the operation of the machine so that the letter spacing along the lines on the printing plate will be automatically performed. It is desirable, however, in a machine of this character, that this spacing operation be capable of manual as well as automatic control. To accomplish this I provide a spacing bar 115 in the forward portion of the keyboard. This bar extends transversely across the entire keyboard and is mounted on two levers 116 adjacent the side members of the frame. These levers 116, as shown in Fig. 5, are preferably pivoted upon the same shaft 49 on which the other key-levers are pivoted. Above the spacing levers 116 is a transverse shaft 117 which carries two levers 118, these levers being positioned preferably directly above the levers 116. One arm of each of said levers 118 is pivotally connected by a link 119 to a lever 116. One of the levers 118 has another arm 120 which is connected by a link 121 to an arm 122 on the escapement lever M. The link 121 passes through a hole in the arm 120 and has a couple of

nuts 123 whereby the arm 120 will actuate the link 121 and escapement lever M in one direction but will have a movement relative to said link 121 in the other direction. The connections between the link 121 and the arm 120 and between the link 110 and the arm 74 permits the escapement to be operated either automatically or manually without interference.

I also provide mechanism whereby the carriage may be manually released from the escapement and free to make a complete shift independent of the escapement. In order to do this I construct the escapement wheel so that it will rotate independently of the shaft 95 on which it is mounted (see Figs. 9, 10, 11 and 12) and so that it will constitute one toothed member of a clutch. The other toothed member 130 of the clutch is splined to rotate with but to slide longitudinally of the shaft 95 and this clutch member is yieldingly held in engagement with the escapement wheel clutch member by means of a spring 131 on the outer end of the shaft 95. By shifting the clutch member 130 the escapement wheel will be released from the shaft 95 and the carriage can then shift independently of the escapement wheel. I provide a key 132 in the keyboard for controlling this clutch. This key 132 is mounted on a key-lever 133 (Figs. 4, 5 and 11) which is pivoted on the key-lever shaft 49 adjacent one side member of the frame, and a spring 134 yieldingly holds this lever in its proper position. A link 135 is connected between the shift lever 133 and a short arm 136 on a transverse shaft 137. This shaft 137 (see Figs. 5 and 9) has another short arm 138 adjacent the other side of the frame, which arm 138 is connected by a link 139 to one arm of a bell crank lever 140. The bell crank lever 140 is pivoted at 141 on the frame of the machine and its other arm is connected with the clutch member 130. Thus by depressing the shift key 132 the clutch member 130 will be separated from the escapement wheel clutch member and the escapement wheel will thereby be disconnected from the shaft 95, leaving the carriage free to make a complete shift under the action of the spring drum 97. I also provide a line-lock mechanism which operates to automatically lock the keys against depression when the end of a line is reached on the printing plate A. In Figs. 5 and 10 it will be seen that the spring drum 97 is mounted upon a shaft 145 which is supported in two lugs 146 depending from the frame of the machine. This shaft carries a cam 147 on which rides a roller 148 mounted on a curved arm 149. The arm 149 is pivoted at 150 on the frame of the machine and its other end is pivotally connected to a link 151 which extends downwardly and is connected to the end of a 100

stop dog 152, the stop dog 152 being pivoted at 153 to the frame of the machine. This stop dog 152 is adapted, under the control of the cam 149, to be dropped down into the path of a stop lug 154 carried on the link 76 which operated the universal bar 68. This stop lug is so positioned that when it engages the stop arm 152 it prevents the return of the universal bar and thereby locks up all of the keys against depression. The cam 147 is so proportioned that when the end of the line, which is being embossed on the plate A, is reached the low part of the cam 147 will be in position to permit the roller 148 and arm 149 to drop and also the stop arm 152 into the path of movement of the stop lug 154, thus preventing the return of the universal bar and the consequent locking up of the keys against further depression.

The printing plate A is adapted to be held by the carriage K while the embossing operation is being performed. It is necessary that the plate should be held quite firmly during the embossing operation but capable of being readily removed or inserted. I provide two gripping members 160 and 161 (see Fig. 2) on the carriage K. These gripping members have grooves on their opposed edges for holding the printing plate by the edges thereof. The gripping member 161 is pivoted at 162 on the carriage and a comparatively strong spring 163 yieldingly presses this gripping member into engagement with the edge of the plate A to grip the plate firmly between the two gripping members. The gripping member 161 has a cam surface 164 at one end which engages a correspondingly shaped cam lug 165 on the frame when the carriage reaches its extreme left hand position. These cam surfaces coöperate to actuate the gripping member 161 and relieve the plate A of the pressure thereof so that the plate may be readily removed or inserted, as desired.

What I claim is:

1. The combination with a die-carrying wheel, of means for rotating said wheel, selective mechanism for arresting the motion of said wheel to bring any desired die carried by said wheel into operative position, and a link and lever connection between said carrying wheel and rotating means controlled by said motion arresting mechanism for automatically moving said wheel bodily to cause the operation of the die so positioned.

2. The combination of a die carrying wheel, continuously operative means for driving said wheel, means for selectively arresting the motion of said wheel in predetermined positions, and a link and lever connection between said die-carrying wheel and said wheel driving means for automatically moving said wheel bodily to operate a

die carried thereby whenever the rotation of said wheel is arrested.

3. The combination of a pair of rotary die-carrying members, and means for simultaneously stopping the rotation of said members and for bodily moving said members automatically toward each other, upon the stopping of said rotation.

4. The combination of rotary die-carrying wheels having a plurality of dies on their peripheries and positioned in edgewise relation, means for continuously rotating said die-wheels, means for arresting said rotation, and means controlled by said rotating means for bodily moving the peripheries of said wheels toward and from each other, when said rotation is arrested.

5. The combination of rotary die-carrying wheels having a plurality of dies on their peripheries and positioned in edgewise relation, means for rotating said die-wheels, key-controlled means for stopping the rotation of said wheels, and means under the control of said stopping means for bodily moving both of said wheels relatively to each other.

6. The combination of a pair of die-wheels mounted on supports to oscillate bodily in arcs having a common center for moving their peripheries toward and from each other, means for rotating said die-wheels upon their own axes, key-controlled means for stopping said wheels and oscillating them about their common center.

7. The combination of a pair of rotary die-wheels, oscillatory supports for said die-wheels operable about a common axis, means for rotating said die-wheels, and key-controlled mechanism for oscillating said supports about their axis.

8. The combination of a pair of rotary die-carrying wheels bodily movable with respect to each other, means for continuously rotating said wheels about their axis, means for arresting said rotation, and means controlled by said rotating means for bodily shifting said wheels relatively to each other.

9. The combination of a pair of rotary die-wheels, supports for said wheels oscillatable about a common axis, means for rotating said die-wheels, means for stopping said die-wheels at a predetermined point in their rotation, and means under control of the said stopping means for bodily oscillating said wheels.

10. The combination of rotary die-carrying members, oscillatory mountings therefor arranged to swing on a common axis which lies in a plane substantially parallel to the plane in which the die-carrying members lie when in embossing position, a common driving member for said die-carrying members, means for stopping the rotation of said common driving member, and means operable by the stopping of said common mem-

ber for swinging the said mountings on their axis.

11. The combination of rotary die-carrying members, oscillatory mountings therefor arranged to swing on a common axis which lies in a plane substantially parallel to the plane in which the die-carrying members lie when in embossing position, a common driving member for said die-carrying members, means for stopping the rotation of said common driving member, means operable by the stopping of said common member for swinging the said mountings on their axis, and means for alining corresponding portions of said die-carrying members with respect to each other.

12. The combination of rotary die members, means for bodily moving said die members with respect to the material to be embossed, a constantly rotating shaft, means rotating therewith for rotating said die members, means for stopping said rotating means, and means under the control of said stopping means for bodily actuating said die members.

13. The combination of a pair of rotary die members arranged to be bodily moved about a common axis, a plurality of key-operated stopping means, and means under the control of said stopping means for bodily actuating said die members.

14. The combination of a pair of rotary die members arranged to be bodily moved about a common axis, a plurality of key-operated stopping means, means under the control of said stopping means for bodily actuating said die members, and means for automatically restoring said die wheels to their normal open position.

15. The combination of a constantly rotating arm, a plurality of key-operated pins adapted to be projected into the path of and arrest the rotation of said arm, a pair of rotary die wheels adapted to stop rotating by the stopping of said arm, and means operable when said arm is arrested for bodily actuating said die wheels to compress therebetween the material to be embossed.

16. The combination of a pair of normally separated die wheels, means for rotating said die wheels in unison, a rotary arm, means for arresting the rotation of said arm at a predetermined point whereby to arrest the rotation of said die wheels, and means automatically operable by the arresting of said arm for bodily closing said die wheels upon the material to be embossed.

17. The combination of a pair of movable supports, coöperating die wheels carried thereby, a constantly rotating shaft, common means driven from said shaft for rotating said die wheels in unison, means for arresting said common means to stop the

rotation of the die wheels at a predetermined point, and means operable by the arrest of said common means for actuating said supports to bodily move said die wheels.

18. The combination of a pair of movable supports, coöperating die wheels carried thereby, a constantly rotating shaft, common means driven from said shaft for rotating said die wheels in unison, means for arresting said common means to stop the rotation of the die wheels at a predetermined point, means operable by the arrest of said common means for actuating said supports to bodily move said die wheels, and mechanism operated by said support actuating means for alining corresponding points on the peripheries of said die wheels as said die wheels are bodily moved.

19. The combination of a pair of synchronously rotating peripherally opposed die members having a plurality of complementary peripheral dies, a plurality of stopping devices corresponding to the dies on said members for arresting the rotation of said members, and means for bodily shifting both of the arrested die members toward each other.

20. The combination of a pair of synchronously rotating peripherally opposed die members having a plurality of complementary peripheral dies, a plurality of stopping devices corresponding to the dies on said members for arresting the rotation of said members, means for bodily shifting both of the arrested die members toward each other, and means engaging said die members for registering the particular opposed complementary dies as said die members come together.

21. The combination of complementary opposed die members rotating in synchronism, means for moving said die members toward each other, a rotating member rotating in synchronism with said die members, means for arresting the rotation of said rotating member, and means responsive to the arrest of the rotating member for causing the operation of said die member moving means.

22. The combination of complementary opposed die members rotating in synchronism, means for moving said die members toward each other, a rotating member rotating in synchronism with said die members, means for arresting the rotation of said rotating member, means responsive to the arrest of the rotating member for causing the operation of said die member moving means, and means for registering said die members as they move together.

23. The combination of a pair of complementary opposed die members having complementary dies distributed about their peripheries, a constantly rotating shaft,

- common means on said shaft for rotating said die members in synchronism, an arm carried by and rotating with said common means, a plurality of stop devices corresponding to the dies on said die members and adapted to arrest the rotation of said arm, and means responsive to the arrest of said arm for bodily bringing said die members together.
24. The combination of a pair of complementary opposed die members having complementary dies distributed about their peripheries, a constantly rotating shaft, common means on said shaft for rotating said die members in synchronism, an arm carried by and rotating with said common means, a plurality of stop devices corresponding to the dies on said die members and adapted to arrest the rotation of said arm, means responsive to the arrest of said arm for bodily bringing said die members together, and means engaging the die members for registering the particular opposed complementary dies as said die members come together.
25. The combination of a pair of peripherally opposed die members having dies distributed around their peripheries, a pair of supports for said die members pivoted to rock about a common axis, a common shaft having its longitudinal axis disposed in the plane in which the complementary dies meet, a common driving member on said shaft and connections therewith for driving said die members, an arm rotating with said common driving member, a plurality of stop devices corresponding to the dies on said die members for arresting the rotation of said arm and said die members, and actuating means on said shaft responsive to the arrest of said arm for rocking said supports to bring the die members together.
26. The combination of a pair of peripherally opposed die members having complementary dies distributed around their peripheries, a pair of supports for said die members pivoted to rock about a common axis, a common shaft having its longitudinal axis disposed in the plane in which the complementary dies meet, a common driving member on said shaft and connections therewith for driving said die members, an arm rotating with said common driving member, a plurality of stop devices corresponding to the dies on said die members for arresting the rotation of said arm and said die members, actuating means on said shaft responsive to the arrest of said arm for rocking said supports to bring the die members together, and means for releasing said arm.
27. The combination of a pair of peripherally opposed die members having dies distributed around their peripheries, a pair of supports for said die members pivoted to rock about a common axis, a common shaft having its longitudinal axis disposed in the plane in which the complementary dies meet, a common driving member on said shaft and connections therewith for driving said die members, an arm rotating with said common driving member, a plurality of stop devices corresponding to the dies on said die members for arresting the rotation of said arm and said die members, actuating means on said shaft responsive to the arrest of said arm for rocking said supports to bring the die members together, means for engaging said die members as they come together to register the particular complementary dies, and means for releasing said arm.
28. The combination of a pair of peripherally opposed die members having complementary dies distributed around their peripheries, a pair of supports for said die members pivoted to rock about a common axis, a common shaft having its longitudinal axis disposed in the plane in which the complementary dies meet, a common driving member on said shaft and connections therewith for driving said die members, an arm rotating with said common driving member, a plurality of stop devices corresponding to the dies on said die members for arresting the rotation of said arm and said die members, actuating means on said shaft responsive to the arrest of said arm for rocking said supports to bring the die members together, means for engaging said die members as they come together to register the particular complementary dies, and means for releasing said arm.
29. The combination of a pair of peripherally opposed die members having complementary dies distributed around their peripheries, a pair of supports for said die members pivoted to rock about a common axis, a common shaft having its longitudinal axis disposed in the plane in which the complementary dies meet, a common driving member on said shaft and connections therewith for driving said die members, an arm rotating with said common driving member, a plurality of stop devices corresponding to the dies on said die members for arresting the rotation of said arm and said die members, actuating means on said shaft responsive to the arrest of said arm for rocking said supports to bring the die members together, means for engaging said die members as they come together to register the particular complementary dies, and means for releasing said arm, a carriage for holding the material to be operated upon, and means for shifting said carriage after each bodily movement of said die members.
30. The combination of opposed rotary die members, mechanism for bodily moving said die members toward and from each other, a carriage for holding between said die members the material to be operated

upon, and means under the control of said mechanism for shifting the carriage relatively to the die members.

31. The combination of a pair of opposed rotary die members, a constantly rotating shaft, a pair of complementary cams carried by said shaft adapted normally to rotate therewith, means for causing a relative rotation of said cams, and means actuated thereby for bodily moving said die members.

32. The combination of opposed rotary die members mounted to rock upon a common axis, a constantly rotating shaft having its axis radial to the arc in which the die members move and passing through said common axis, and means carried by said shaft for rocking both of said die members about said common axis.

33. The combination of opposed rotary die members mounted to rock upon a common axis, a constantly rotating shaft having its axis radial to the arc in which the die members move and passing through said common axis, means carried by said shaft for rocking both of said die members about said common axis, and means operable as said die members approach each other for engaging the die members to register complementary die portions on said die members.

34. The combination of peripherally opposed die members having a plurality of complementary dies on their peripheries and mounted to rock about a common axis positioned in the plane in which said complementary dies meet, a constantly rotating shaft having its longitudinal axis positioned in said plane, a common member on said shaft rotatable in a plane perpendicular to said plane for rotating the die members, a pair of complementary cams forming a driving connection between said shaft and said driving member, means for arresting the rotation of one of said cams and said driving member to cause a relative rotation of said cams, and means responsive to the relative rotation of said cams for rocking said die members about said common axis.

35. The combination of peripherally opposed die members having a plurality of complementary dies on their peripheries and mounted to rock about a common axis positioned in the plane in which said complementary dies meet, a constantly rotating shaft having its longitudinal axis positioned in said plane, a common member on said shaft rotatable in a plane perpendicular to said plane for rotating the die members, a pair of complementary cams forming a driving connection between said shaft and said driving member, means for arresting the rotation of one of said cams and said driving member to cause a relative rotation of said cams, means responsive to the relative rotation of said cams for rocking said die members about said common axis, and

means also responsive to the relative rotation of said cams for engaging the die members to register the particular complementary dies as said die members come together.

36. The combination of peripherally opposed die members having a plurality of complementary dies on their peripheries and mounted to rock about a common axis positioned in the plane in which said complementary dies meet, a constantly rotating shaft having its longitudinal axis positioned in said plane, a common member on said shaft rotatable in a plane perpendicular to said plane for rotating the die members, a pair of complementary cams forming a driving connection between said shaft and said driving member, means for arresting the rotation of one of said cams and said driving member to cause a relative rotation of said cams, means responsive to the relative rotation of said cams for rocking said die members about said common axis, means also responsive to the relative rotation of said cams for engaging the die members to register the particular complementary dies as said die members come together, a carriage for the material to be operated upon by said die members, and means also responsive to the relative rotation of said cams for shifting the carriage.

37. The combination of a pair of peripherally opposed die carrying wheels, supports therefor mounted to rock about a common axis, a constantly rotating shaft, a cam member rotatable with but longitudinally slidable on said shaft, a complementary cam member rotatable independently of said shaft, means connected therewith for rotating said die wheels, means for holding said cams in registering position for rotation in unison, means for holding said complementary cam member to cause the other cam member to move longitudinally on said shaft, and means operated by said longitudinally movable cam for rocking said die wheel supports about their common axis.

38. The combination of a pair of peripherally opposed die carrying wheels, supports therefor mounted to rock about a common axis, a constantly rotating shaft, a cam member rotatable with but longitudinally slidable on said shaft, a complementary cam member rotatable independently of said shaft, means connected therewith for rotating said die wheels, means for holding said cams in registering position for rotation in unison, means for holding said complementary cam member to cause the other cam member to move longitudinally on said shaft, and toggles operated by said longitudinally movable cam for rocking the die wheel supports about their common axis.

39. The combination of a pair of peripherally opposed die carrying wheels, supports therefor mounted to rock about a com-

mon axis, a constantly rotating shaft, a cam member rotatable with but longitudinally slidable on said shaft, a complementary cam member rotatable independently of said shaft, means connected therewith for rotating said wheels, means for holding said cams in registering position for rotation in unison, means for holding said complementary cam member to cause the other cam member to move longitudinally on said shaft, means operated by said longitudinally movable cam for rocking said die wheel supports about their common axis, and means responsive to the longitudinally movable cam for engaging the die wheels as they come together for positioning complementary portions of their peripheries relatively to each other.

40. The combination of a pair of peripherally opposed die carrying wheels, supports therefor mounted to rock about a common axis, a constantly rotating shaft, a cam member rotatable with but longitudinally slidable on said shaft, a complementary cam member rotatable independently of said shaft, means connected therewith for rotating said die wheels, means for holding said cams in registering position for rotation in unison, means for holding said complementary cam member to cause the other cam member to move longitudinally on said shaft, means operated by said longitudinally movable cam for rocking said die wheel supports about their common axis, a carriage for positioning the work between the die wheels, and means controlled by said longitudinally movable cam for shifting said carriage during each cycle of operation of said mechanism.

41. The combination of a pair of rotary die wheels, mechanism for rotating and for bodily actuating said die wheels, a rotary member, a stop device for stopping said rotary member to control the operation of said die wheel rotating and bodily actuating mechanism, a key for operating said stop device, and means controlled by said die wheel mechanism for restoring said key and stop device.

42. The combination of a constantly rotating shaft, a pair of complementary members on said shaft normally rotating in unison, means for stopping the rotation of said members to cause a relative rotation of said members, opposed die members, and means responsive to the relative rotation of said complementary members for actuating said die members.

43. The combination of a constantly rotating shaft, a pair of complementary members normally rotating in unison with the said shaft, an arm carried by and rotating with one of said complementary members, means interposable in the path of said arm for stopping the rotation of its complemen-

tary member, a pair of opposed die members, and means responsive to the relative rotation of said complementary members for actuating said die members.

44. The combination of a constantly rotating shaft, a pair of complementary members normally rotating in unison with the said shaft, an arm carried by and rotating with one of said complementary members, a stop pin adapted to be interposed in the path of said arm to stop its complementary member, and means responsive to the relative rotation of said complementary member for actuating said die wheels.

45. The combination of a constantly rotating shaft, a pair of complementary members normally rotating in unison with the said shaft, an arm carried by and rotating with one of said complementary members, a stop pin adapted to be interposed in the path of said arm to stop its complementary member, means responsive to the relative rotation of said complementary member for actuating said die wheels, and means responsive to the relative rotation of said complementary members for restoring said stop pin to release said arm.

46. The combination of a constantly rotating shaft, a pair of complementary cams on said shaft normally driven thereby in unison, a pair of opposed die members having complementary dies, means connected with one of said complementary cams for rotating said die members, an arm carried by said same cam member, a plurality of stop pins, a corresponding key for each stop pin for projecting said pin in the path of said arm to stop its cam member and the die wheels, means operated by said other cam in response to the relative rotation of said cams for bodily actuating said die wheels, and means under the control of said bodily actuating means for restoring the key and stop pin.

47. The combination of a constantly rotating shaft, a pair of complementary cams on said shaft normally driven thereby in unison, a pair of opposed die members having complementary dies, means connected with one of said complementary cams for rotating said die members, an arm carried by said same cam member, a plurality of stop pins, a corresponding key for each stop pin for projecting said pin in the path of said arm to stop its cam member and the die wheels, means operated by said other cam in response to the relative rotation of said cams for bodily actuating said die wheels, a universal bar common to all of said keys, and means under the control of said bodily actuating means for restoring the operated key and stop pin.

48. The combination of a pair of oppositely rotating die-wheels, means for bodily moving said die-wheels toward and from

each other, and guide means slidably mounted in bearings positioned closely adjacent the impression point of said die-wheels and adapted to coöperate directly with said die-wheels to hold said wheels in position to register as they come together.

49. The combination of a pair of oppositely rotary die-wheels, means for bodily moving said die-wheels toward and from each other, and a pair of movable pins slidably mounted in bearings positioned closely adjacent the impression point of said die-wheels and adapted to engage said die-wheels and hold them in position to register as they come together.

50. The combination of a pair of oppositely rotary die-wheels having a plurality of circumferentially disposed complementary dies, means for bodily moving said die-wheels toward and from each other, and means slidably mounted in bearings closely adjacent the impression point of said die-wheels adapted to engage the sides of said die-wheels adjacent the registering portions thereof to register the particular dies for each wheel as said wheels come together.

51. The combination of opposed rotary die wheels having a plurality of circumferentially distributed complementary dies and having a plurality of corresponding slots, means for rotating said die wheels, means for stopping the rotation of said die wheels, means under the control of said stopping means for bodily moving said die-wheels toward each other, and pins adapted to enter the slots corresponding to the dies in juxtaposition on said wheels for alining said dies as the wheels come together.

52. The combination of opposed rotary die wheels having a plurality of complementary dies on their peripheries, means for selectively stopping said die wheels, mechanism for bodily actuating said die-wheels to move them toward and from each other, a carriage for holding the work with respect to the dies, and means under the control of said bodily actuating mechanism for shifting the carriage at each operation of said die-wheels.

53. The combination of opposed rotary die wheels having a plurality of complementary dies on their peripheries, means for selectively stopping said die wheels, mecha-

nism for bodily actuating said die wheels to move them toward and from each other, 55 a carriage for holding the work with respect to the dies, and an escapement mechanism under the control of said bodily actuated mechanism for shifting the carriage at each operation of the die wheels. 60

54. In combination, a rotary die-carrying wheel having its axis of rotation confined to a single plane, means for rotating said wheel, selective mechanism for arresting the motion of said wheel to bring any desired 65 die carried by said wheel into operative position, and link connections between said die-carrying wheel and said rotating means controlled by said motion arresting mechanism for automatically moving said wheel 70 bodily to cause the operation of the die so positioned.

55. The combination of a die-carrying wheel having its axis of rotation confined to a single plane, continuously operating 75 mechanism for driving said wheel, means for selectively arresting the motion of said wheel in predetermined positions, and link connections between said die-carrying wheel and the operating mechanism therefor for automatically moving said wheel 80 bodily to operate a die carried thereby whenever the rotation of said wheel is arrested.

56. In combination, a stationary pivot, a shaft carried by said pivot transversely 85 thereof, a die-carrying wheel carried by said shaft, continuously operating means for driving said wheel, means for selectively arresting the motion of said wheel in predetermined positions, and mechanical connecting means between said die-carrying wheel and the operating mechanism therefor comprising a toggle lever and cam for automatically moving said shaft about said pivot to operate a die carried on said wheel 95 whenever the rotation of said wheel is arrested.

In testimony whereof I have signed my name to this specification, in the presence of two subscribing witnesses, on this 3rd day 100 of June, A. D. 1914.

CLARENCE E. STEERE.
